(57) CLAIM

The ornamental design for a spice rack, as shown and described.

DESCRIPTION

FIG. 1 is a top perspective view of the spice rack in a state of use;

FIG. 2 is a front view thereof in another state of use;

FIG. 3 is a rear view thereof;

FIG. 4 is a side view;

FIG. 5 is a second side view thereof;

FIG. 6 is a top view thereof;

FIG. 7 is a bottom view thereof; and,

FIG. 8 is another perspective view of the spice rack, shown in a state of use with environment.

The broken lines in the drawings show portions of the spice rack and form no part of the claimed design. The additional set of broken lines in FIG. 8, showing components within the spice rack, show environment and form no part thereof.

1 Claim, 6 Drawing Sheets
